(57) CLAIM

The ornamental design for the retailer display, as shown and described.

DESCRIPTION

FIG. 1 is a perspective view of a retailer display according to the present invention;

FIG. 2 is a top plan view of the retailer display of FIG. 1; FIG. 3 is a front elevational view of the retailer display of FIG. 1;

FIG. 4 is a bottom plan view of the retailer display of FIG. 1;

FIG. 5 is a left-side elevational view of the retailer display of FIG. 1; and,

FIG. 6 is a cross sectional view taken along line 6—6 of FIG. 5.

The rear elevational view is a mirror image of the front elevational view of FIG. 3.

The right side elevational view is a mirror image of the left side elevational view in FIG. 5.

The broken line showing of a shoe in FIG. 1 is for illustrative purposes only and forms no part of the claimed design.

The surface(s) or portion(s) of the article not shown in the drawing or described in the specification form(s) no part of the claimed design.
